(57) **CLAIM**

The ornamental design for a multi-function charging cable, as shown and described.

DESCRIPTION

FIG. 1 is a top, front, right side perspective view of a multi-function charging cable, showing my new design; FIG. 2 is a front elevational view thereof; FIG. 3 is a rear elevational view thereof; FIG. 4 is a left side elevational view thereof; FIG. 5 is a right side elevational view thereof; FIG. 6 is a top plan view thereof; FIG. 7 is a bottom plan view thereof; and, FIG. 8 is a bottom, front, right side perspective view of the multi-function charging cable.

In the drawings, the broken lines are for the purpose of illustrating portions of the multi-function charging cable that form no part of the claimed design. In FIGS. 1, 2, 3, 4, 5 and 8 the cable is shown with a symbolic break in its length. The appearance of any portion of the article beyond the break lines forms no part of the claimed design.
